RECORDING OF SOUND

Berthold Freund, Berlin-Schoeneberg, Germany,
assigner to Tobis, Tonbild-Syndikat A. G., Berlin, Germany, a corporation of Germany

Application October 16, 1936, Serial No. 105,846
In Germany July 30, 1935

4 Claims. (Cl. 179—100.3)

This invention relates to the recording of sound, and has for its principal object the provision of an improved recording system and method of operation whereby the difficulties heretofore encountered in the operation of anti-ground-noise systems are avoided.

It is known to record sound by systems involving the use of a galvanometer or light valve actuated in accordance with the audio frequency to be recorded and to further subject these recording elements to a current which is varied as the volume of the recorded signals for the purpose of eliminating the background noise otherwise produced by the transparent portion of the record. The operation of such systems sometimes involves the difficulty that the influence of the volume responsive current must be exerted gradually to avoid the production of spurious sounds and must be exerted quickly enough to prevent cutting-off of the recorded peaks.

It has been attempted to avoid this difficulty by recording the sound on a single track without the use of volume responsive current and utilizing such current subsequently during the rerecording operation. This procedure, however, has the disadvantage that the background noise is likely to be rerecorded together with the desired sound.

In accordance with the present invention these difficulties are avoided by a procedure which involves first recording the sound in the form of a push-pull record and subsequently rerecording from this push-pull record to a single track record which is at the same time subjected to a shading effect dependent on a volume responsive current which may be derived either from the push-pull record or from the original source of sound.

The invention will be better understood from the following description when considered in connection with the accompanying drawing and its scope will be indicated by the appended claims.

Referring to the drawing,

Fig. 1 illustrates a system arranged in accordance with the invention,

Fig. 2 is similar to Fig. 1 in some respects but differs therefrom with respect to the size of the photocell utilized to pick up the volume responsive current, and

Fig. 3 illustrates the application of the invention to the production of a variable density record.

The system of Fig. 1 includes a microphone 1 or other pick-up device on which are impressed the sounds to be recorded. Upon the light sensi-

tive film 3 are produced by means of a push-pull recorder 2 a push-pull sound record wherein the positive and negative half cycles are recorded on separate tracks which are spaced from one another in accordance with a known method of push-pull recording. These tracks are rerecorded upon a film in the form of a single sound track 6 by means of photocells 4 and 5, which are connected in push-pull. In addition to the cells 4 and 5, a photoelectric cell 7 shown as extending entirely across the sound record, is utilized to produce a volume responsive current through which a background noise reduction track is produced.

The arrangement of Fig. 2 differs from that just described in that a photoelectric cell 10 is provided with a width A so great that the desired gradual increase and decrease of the volume responsive or noiseless sound track is automatically produced. It is essential that the push-pull recorders 4 and 5 and the anti-noise reproducers 7 or 10 be so spaced longitudinally of the push-pull record as to produce the proper relation between sound track 6 and the anti-noise track 8.

The system of Fig. 3 is designed for the noiseless rerecording to a sound record of the variable density type as distinguished from the variable area type record of Figs. 1 and 2. In this case, the currents supplied from cells 4 and 5 and from the cell 7 are superposed and used for the combined recording of the cell track and the anti-background noise track. The joint recording device is indicated at 15 and may be of any of the many suitable forms known to those skilled in the art. It is advantageous to have the primary push-pull record 3 recorded positive for the reason that the sound modulations appear light or transparent and the remainder of the record appears black or dark. This is easily accomplished by a suitable adjustment of the recording apparatus. In that case, the separate copy of the push-pull record as a positive is not necessary in order to effect the transformation to the noiseless or background noise track in accordance with the invention. In accordance with the invention, noiseless master records in standard noiseless track form may be produced and it is particularly feasible to obtain noiseless master records that may be directly copied, for instance, the recorded push-pull variable width track by means of a single transformation, if necessary, for the insertion of suitable correcting means.

It will be readily understood that the push-pull photocells 4 and 5 and the volume responsive current cell 7 or 10 are so spaced with respect

to one another longitudinally of the film that a proper cooperative relation may be maintained between the single track 6 and the anti-noise track 8. It will also be apparent that only half 5 the width of the primary record may be utilized to derive the volume responsive current and other modifications may be made without departing from the spirit and scope of the invention.

I claim as my invention:

- 10 1. The combination of means for recording sound in the form of a push-pull record having the positive and negative half cycles spaced from one another, means for rerecording said sound from said push-pull record to a single track record, and means for deriving from said push-pull record an anti-noise track which is dependent 15 on the volume of said sound.
2. The combination of means for recording sound in the form of a push-pull record having the positive and negative half cycles spaced from one another, means for rerecording said sound from said push-pull record to a single track record, and means including a light responsive 20

element responsive to said positive and negative half cycle records for producing an anti-noise track in cooperative relation with said single track.

3. The combination of means for recording sound in the form of a push-pull record having the positive and negative half cycles spaced from one another, means for rerecording said sound from said push-pull record to a single track record, and means including a light responsive element of relatively great width for rerecording in 10 cooperative relation with said single track.

4. The combination of means for recording sound in the form of a push-pull record having the positive and negative half cycles spaced from one another, means for rerecording said sound from said push-pull record to a single track record, and means including a light responsive element spaced from said push-pull means for producing an anti-noise track in cooperative relation with said single track. 15 20

BERTHOLD FREUND.
